UNITED STATES PATENT OFFICE.

EDWIN N. LIGHTFOOT, OF NEW YORK, AND ROBERT C. BECK, OF BROOKLYN, NEW YORK, ASSIGNORS TO THE CUTLER-HAMMER MFG. CO., OF MILWAUKEE, WISCONSIN, A CORPORATION OF WISCONSIN.

FILLING MACHINE.

Application filed August 13, 1921, Serial No. 492,028. Renewed December 11, 1924.

To all whom it may concern:

Be it known that we, EDWIN N. LIGHTFOOT and ROBERT C. BECK, citizens of the United States, residing, respectively, at New York, in the county of Bronx and State of New York, and Brooklyn, in the county of Kings and State of New York, have invented new and useful Improvements in Filling Machines, of which the following is a specification.

This invention relates to a filling machine.

More particularly it relates to a machine for filling the tubular jacket of an electric heater with powdered or granular insulation, which positions the resistor thereof in the jacket and insulates it therefrom.

An object of the invention is to provide an efficient filling machine for rapidly filling tubular jackets of electric heaters with insulation and compressing the same therein around and about the resistor thereof while centrally positioning the resistor therein.

Another object is to provide a filling machine wherein a plurality of such tubular heaters may be filled simultaneously and wherein the flow of insulation to each jacket is independently controlled so that the flow of insulation ceases when the jacket is filled.

Other objects and advantages will herein-after appear.

The views of the drawings are:

Fig. 1 is a front elevation of the filling machine.

Fig. 2 is an end elevation of the filling machine.

Fig. 3 is an enlarged side elevation of the vibratory carrier, its vibrator and the tamper lifter.

Fig. 4 is an enlarged horizontal section on line 4—4 of Fig. 3, showing the funnel cover.

Fig. 5 is a horizontal section on line 5—5 of Fig. 3.

Fig. 6 is a side elevation, partly in section, of the lower vibratory carrier bracket.

Fig. 7 is a horizontal section on line 7—7 of Fig. 6.

Fig. 8 is an enlarged front elevation of the vibrator and tamper lifter operating

mechanism and the electromagnetically operated belt shifter.

Fig. 9 is a horizontal section on line 9—9 of Fig. 8.

Fig. 10 is a vertical section through the vibrator, tamper lifter and upper carrier bracket.

Fig. 10^a is a horizontal section through the tamper on line 10^a—10^a of Fig. 10.

Fig. 11 is a horizontal section on line 11—11 of Fig. 10.

Fig. 12 is a horizontal section on line 12—12 of Fig. 10.

Fig. 13 is an enlarged vertical section through the tension rod adjustable support on line 13—13 of Fig. 1.

Fig. 14 is an enlarged front elevation of the belt shifter operating mechanism.

Fig. 15 is an end elevation, partly in section, on line 15—15 of Fig. 14.

Fig. 16 is a vertical section on line 16—16 of Fig. 14.

Fig. 17 is a plan view of a part of the apparatus.

Fig. 18 is an elevation, partly in section, of part of the apparatus shown in Fig. 1.

Fig. 19 is a horizontal section on line 19—19 of Fig. 18.

Fig. 20 is an elevation of the same part of the apparatus shown in Fig. 18, viewed from a different angle.

Fig. 21 is a horizontal section on line 21—21 of Fig. 20.

Fig. 22 is a diagram of the electrical connections for the controller and the belt shifter operating solenoid.

The filling machine comprises, in general, a plurality of filling units 1 supported in a frame 2, each filling unit having a vibratory carrier 3 for a heater jacket 4, a carrier vibrator 5, a container 6 for insulation, a tamper 7 which serves to center the heater resistor 8 in the jacket and to compress the insulation in the jacket, a tamper lifter 9, a resistor support 10, which places the resistor under sufficient tension to maintain the same fairly taut, an electromagnetically controlled spring actuated belt shifter 11 for stopping the operation of the unit when the heater jacket therein is filled with insula-

90

95

100

tion, and a controller 12 for the belt shifter magnet.

Frame.

5 The frame 2 (Figs 1 and 2) supporting the filling units is made up of right and left end legs 13 fastened together by spacing tie rods 14.

10 Front and rear bed channels 15 fastened together by spacing tie rods 16 extend the width of the frame and rest upon and are bolted to the end legs 13.

15 Right and left end uprights 17 standing upon and bolted to the bed channels 15 are fastened together by spacing tie rods 18.

20 Cross rails 19 and 20, bolted or otherwise fastened to the end uprights 17, are arranged to have fastened thereto the carrier vibrator and tamper lifter operating mechanism and the belt shifter mechanism respectively of the several filling units, as will more fully hereinafter appear.

25 A cross rail 21 bolted or otherwise fastened to the end legs 13 near the lower end thereof is arranged to support resilient seats for the vibratory carriers of the several filling units, as will more fully hereinafter appear.

30 Upwardly extending angle irons 22 bolted or otherwise fastened to the end uprights 17 have fastened thereto two pairs of transversely extending angle irons 23 and 24.

35 Forwardly extending brackets 25 fastened to the respective pairs of transverse angle irons are arranged to support operating mechanism for the belt shifter controller and resistor support mechanism for the several filling units, as will more fully hereinafter appear.

40 A transverse angle iron 26 bolted to the upwardly extending angle irons 22 and the end uprights 17 assists in making the upper framework rigid.

45 The frame is arranged to support six vertical filling units (only three of which are shown) spaced on ten (10) inch centers, each capable of filling a tubular jacket up to five (5) feet in length.

The illustrated frame has dimensions as follows:

	Inches.
50 Width	63 $\frac{1}{2}$
Extended overall height	162
55 End legs, height	35 $\frac{3}{4}$
depth at base	31
depth at top	15
55 Bed channels, height	7 $\frac{7}{8}$
End uprights, height	38 $\frac{1}{2}$
depth at base	14 $\frac{1}{2}$
depth at top	4 $\frac{1}{4}$
60 Upright angle irons, length from top of end upright	57 $\frac{1}{4}$

Vibratory carrier.

65 The vibratory carrier 3 (Figs. 1, 2, 3 and 6), which may take the form of an elong-

gated square or rectangular rod, is provided with an upper bracket 27 and a lower bracket 28, between which the heater jacket 4 is supported.

These brackets are adjustably fastened to 70 the carrier so that heater jackets of different lengths may be accommodated.

The lower arm of the upper bracket 27 (Fig. 3) carries a funnel 29 having seated in the lower end thereof a removable bushing 30, recessed to receive the upper end of the heater jacket 4.

75 A clamp 31 fastened to legs 32 downwardly extending from the lower arm of the bracket 27 holds the bushing 30 in place. The clamp 31 has an opening through which the upper end of the heater jacket extends. A gasket 33 is arranged between the bushing and the lower end of the funnel so as to prevent the passage of insulation therebetween.

80 The funnel 29 is provided with a divided cover 34, one section being rigidly fastened to the funnel, while the other section is pivoted thereto so that it may be swung aside 85 so as to allow access to the funnel.

85 The funnel 29, and its cover 34 with a gasket 35 therebetween are rigidly fastened to the lower arm of the upper bracket 27, so as to prevent movement with respect to the bracket while the carrier is vibrating.

90 The container 6 for the insulation is carried by and rigidly fastened to the upper arm of the bracket 27 by means of a bracket arm 6'. The container spout 36 extends through an opening in the funnel cover 34 and is positioned to feed insulation from the container into the funnel 29. The flow of insulation from the container may be regulated by means of a valve 37 in the 105 spout 36.

95 The gasket 35 fits tightly around the spout 36 and prevents the escape of insulation through the top of the funnel.

100 The flow of insulation from the container is assisted by means of a piston 38 resting on top of the insulation and guided by piston rod 39 connected thereto and extending through an opening in the cover 40 of the container.

105 The position of the piston rod 39 indicates the amount of insulation in the container. Thus as the amount of insulation in the container decreases, the length of the piston extending therefrom gradually decreases.

110 The lower bracket 28 (Figs. 6 and 7) has a tapered seat 41 for receiving the electric heater terminal 42 or a temporary plug (or cap) for the lower end of the heater jacket 4. The tapered seat 41 is formed in the upper end or head 43 of a plunger 44, both the head and the plunger being slideable in 115 openings in the lower bracket 28.

120 A cushion 41' of rubber or other suitable material provided in the tapered seat 41 is 125

held in place by a metal ring 43' screwed or otherwise fastened to the head 43.

This cushion 41' seals the outer end of the tubular terminal 42 so as to prevent the escape of insulation through the opening therein while the tubular heater jacket is being filled with insulation.

The tapered seat 41 is held in lifted position by means of a pivoted cam 45 engaging a roller 46 fastened to the lower end of the plunger 44. The plunger is prevented from turning with respect to the bracket 28 by means of a key 47 fastened to the bracket and extending into a longitudinal slot in the plunger.

The piston or plunger 44 may be raised and lowered by means of the pivoted cam 45 arranged within an opening in the lower end of the bracket 28 and cooperating with the roller 46 on the lower end of the plunger. The cam is fixed to a shaft 45' supported in the bracket 28 and is operated by a handle 48. When the piston roller 46 rests in the cam groove 45^a the tapered seat 41 is in elevated position, and is in lowered position when the roller rests in the cam groove 45^b.

To keep the heater jacket 4 straight and thus prevent bending or buckling thereof, it is held intermediate its ends in fixed relation to the vibratory carrier 3. For this purpose a bracket 49 (Figs. 3 and 5) rigidly fastened to the carrier 3 and adjustable thereon has hinged thereto a pair of arms carrying at their outer or free ends removable oppositely grooved or slotted jaws 51 arranged to receive therebetween the jacket 4.

A coil spring 52 interposed between the arms tends normally to hold the jaws apart. The jaws, however, may be clamped against the heater jacket 4 in opposition to the force of the spring 52 by means of a cam 53 hinged to one end of the rod extending through the arms 50 and having a shoulder abutting one of the arms. The cam 53 may be actuated by the handle 53' fastened thereto.

When adjusting a filling unit for accommodating the heater jacket, a bushing 30 having an inner diameter equal to the inside diameter of the jacket is clamped in place at the lower end of the funnel 29.

The upper and lower brackets 27 and 28 are then adjusted so that the particular heater jacket of a definite length may be seated therein. The brackets are then locked in adjusted position on the carrier.

When arranging the jacket in the carrier 60 the tapered seat of the lower bracket 28 is lowered and the heater terminal fastened to the jacket, or the temporary cap or plug for the end thereof, is placed in the lowered tapered seat. The upper end of the jacket is then arranged beneath the bushing 30 and

the lowered tapered seat is raised so that the upper end of the jacket is moved through the opening in the clamp 31 and into the recessed bushing 30. The jacket may then be clamped between the clamping jaws 51 of the intermediate bracket 49. The jacket is now rigidly held in the vibratory carrier.

Carrier vibrator.

The vibratory carrier 3 (Figs. 2 and 6) is resiliently supported by a bracket 55 bolted or otherwise rigidly fastened to the lower frame cross rail 21. The vibratory carrier extends through an opening in the bracket 55 and has an adjustable collar 56 secured thereto. The collar 56 rests upon a compression spring 57 surrounding the carrier 3 and seated on the bracket 55. The resilient support for the vibratory carrier 85 is provided with dust-proof casing 58.

The vibrator by which the carrier 3 is vibrated comprises a rotatable disc 59 (Figs. 3, 8 and 10) mounted upon a shaft 60 carrying in peripheral grooves thereof a plurality of evenly spaced rollers 61 which project beyond the periphery of the disc 59.

These rollers 61 successively engage a roller 62 carried in the upper end of the head 63 fixed to the carrier 3. The head 63, which is adapted to reciprocate in a vertical opening in the vibrator housing 64, is prevented from turning with respect thereto by means of a flat pin 65 extending through an opening in and fixed to the head 63. This pin 65 projects into diametrically opposed vertically disposed slots 66 provided in the vibrator housing.

Longitudinal movement of the rollers 61 is prevented by the housing end cover plate 67 which in cooperation with an interposed gasket 67' serves to keep dirt and other foreign substances out of the vibratory housing.

As the disc 59 is rotated, the vibrator 110 rollers 61 carried thereby successively engage the carrier roller 62 and as a roller 61 engages roller 62 the carrier is forced downward against the action of the spring 57. Then as the roller 61 moves out of engagement with the roller 62, the spring 57 forces the carrier 3 upward until the roller 62 engages the periphery of the disc 59.

Thus, during the rotation of the disc 59 the carrier 3 is rapidly vibrated through a distance determined by the amount which the rollers 61 extend beyond the periphery of the disc 59.

It has been found that satisfactory results are obtained by vibrating the carrier 3 approximately three-sixtyfourths (3/64) of an inch.

The vibratory housing 64 is rigidly secured to a bracket plate 68 as by being cast integrally therewith. The bracket plate 68 130

is bolted or otherwise rigidly fastened to the frame cross rail 19.

The vibrator shaft 60 is journaled in bearings provided in the housing 64 and in a bracket arm 69 (Figs. 8 and 9) formed integrally with the bracket plate 68, or otherwise rigidly fastened thereto. The vibrator shaft carries at its outer end two pulleys 70 and 71, the former being loosely mounted thereon, and the latter fixed thereto so as to rotate therewith. These pulleys 70 and 71 are held in proper position on the shaft 60 by a collar 60' fastened thereto.

The fixed pulley 71 is arranged to be driven, whereby the vibrator disc and rollers carried thereby are caused to rotate to impart vibratory movement to the carrier 3.

The vibration of the carrier 3 causes the insulation to flow freely from the container 6 through the funnel 29 and bushing 30 and down into the heater jacket 4.

The constant vibration of the heater jacket 4 aids in filling with insulation all space around and about a helical resistor arranged within the jacket, and prevents clogging of the insulation in the upper part of the jacket before the lower part is filled.

Common drive.

The pulley 71 is driven from a drive shaft 72 (Figs. 1, 3, 8 and 9) journaled in bearings provided in upwardly projecting rear brackets 73 of the frame and uprights 17. This drive shaft 72 extends the length of the frame and is provided with pulleys 74 fixed thereto. There is one pulley for each filling unit of the machine. The drive shaft pulley 74 is connected with the pulley 71 fixed to the vibrator shaft by means of a belt 75 passing through an opening 75' in the frame cross rail 19.

The brackets 73 in which the drive shaft 72 is journaled are connected at their free ends by means of a tie rod 76 extending through a spacing tube 77.

The drive shaft 72 may be driven from an appropriate source of power, as by means of a belt passing over a pulley 78 fixed to the drive shaft between the left end bracket 73 and a bracket 79 bolted or otherwise rigidly fastened to the left end upright 17 and provided with a bearing for receiving the end of the drive shaft.

As the rate of vibration of each carrier 3 is determined by the speed of rotation of its vibrator shaft 60, it may be varied by varying the relative diameters of the vibrator shaft pulley 71 and the individual driving pulley 74.

Tamper.

The tamper 7 (see Figs. 10 and 10^a) is in the form of a tube having an internal diameter such that the tamper will slide

freely over the helical resistor 8 arranged in the heater jacket 4.

The tubular tamper 7 provided with outwardly extending radial lugs 80 extends into the jacket and serves to center and position the resistor 8 and compress the insulation.

The radial lugs 80, while spacing the tubular tamper from the jacket, allow the free discharge of insulation therebetween.

The tubular tamper 7 (Figs. 2 and 10) extends through the bushing 30 and the funnel 29, and an opening in the cover therefor, through a removable bushing 81 secured to the upper arm of the carrier bracket 27 and into a guide tube 82. This guide tube 82 is supported by the brackets 25 in which it is clamped.

The removable bushing 81 is seated in a pocket 83 on the upper bracket arm and is retained therein by a cap screw 83'.

In order that the tubular tamper 7 may be retained in elevated position when removing a filled jacket from the carrier and placing therein a jacket to be filled, a clamping screw 84 is threaded through the wall of a bushing 81 seated in the pocket 83 in which it is fastened by a screw 83'. This clamping screw 84 has a soft metal tip 84' for engaging the tubular tamper 7. The free end 85' of the clamping screw operating handle 85 is weighted so as to prevent the screw 84 moving in and out due to the vibration of the vibratory carrier.

The tubular tamper 7 has fastened to its upper end a tubular weight 86 (see Fig. 18), which increases the effectiveness of the tamper.

The tubular tamper 7 above the radial spacing lugs at the bottom thereof cooperates with the tubular jacket to form an unobstructed annular passageway for the insulation.

Tamper lifter.

The lifter (see Figs. 10 and 11) for periodically lifting the tubular tamper 7 comprises a pair of rotatable yielding jaws or shoes 87, each fastened to one end of a flat spring 88, the other end of which is fastened to a collar 89 fixed on a rotatable shaft 90.

Each collar is slotted to receive the guide jaw or shoe supported thereby. The shafts 90 are journaled in bearings provided in bracket arms 91 and 94 (see Figs. 8 and 9), the base 92 of which is seated on the bracket plate 68, and bolted or otherwise rigidly fastened thereto and to the frame cross rail 19.

Meshing spur gears 93 located between the bracket arms 91 and 94 are fixed to the shafts 90 so that the rotation of one shaft causes the other to rotate at the same speed but in the opposite direction. The respec-

tive shafts rotate in the directions indicated by the arrows thereon.

The tamper lifter is actuated (see Figs. 8, 9 and 10) from the vibrator shaft 60 by means of a spur gear 95 fastened there-to meshing with an intermediate spur gear 96, which in turn meshes with a spur gear 97 fixed to the rear lifter shaft 90. A collar 90' fastened to the rear lifter shaft 90 holds 10 the gear 97 in proper position. The intermediate spur gear 96, which is for the purpose of rotating the lifter shafts 90 in the proper direction, is fixed to a spindle 96' resting in bearings provided in the 15 bracket arm 69 and in the vibrator housing 64.

As the lifter shafts 90 are rotated the yielding jaws or shoes 87 carried thereby engage the tubular tamper 7 and lift the 20 same a distance of about one-half (1/2) inch and then move out of engagement therewith, allowing the tamper 7 to drop, thus tamping or compressing the insulation in the heater jacket 4.

25 While the tamper is being lifted and dropped periodically, the jacket is gradually filling with insulation; consequently, the insulation is rising higher and higher in the jacket.

30 Thus, while the jaws 87 always lift the tamper 7 the same distance, the point from which the tamper is lifted is continually changing as the insulation rises in the jacket. Therefore the tamper is gradually 35 raised independently of the lifter until the jacket is filled.

Resistor support.

In order that the tubular tamper 7 as it 40 is periodically lifted and dropped may slide freely over the helical resistor 8, it is desirable that the helical resistor be maintained fairly taut; consequently the resistor is kept under tension while the jacket is being filled with insulation.

The support or tension maintaining means (see Figs. 13, 18 and 20) comprises a wire or rod 98 having at its lower end a hook 99 for engaging the upper end of the 50 resistor 8. This wire 98, which may be made of piano wire, extends up through the tubular tamper 7 and the guide tube 82, and at its upper end is rigidly fastened to an arm 100 secured to an adjustable hook rod 55 101.

The hook rod 101, which may be square or rectangular at its upper end and round at its lower end, extends through a guide pipe 102 clamped to the brackets 25. A bushing 102' in the end of the guide pipe 102 prevents the turning of the hook rod 101. The hook rod is held in adjusted position by a clamping screw 103 (see Fig. 13) projecting through the pipe wall and a collar 60 104 fastened thereto at its lower end. The

clamping screw 103 has a soft metal tip 103' which engages the hook rod 101.

While a heater jacket 4 is being placed in the vibratory carrier 3, the upper end of the resistor 8 is connected to the hook 99 of the 70 tensioning wire 98 and the hook rod 101 raised to take up the slack in the resistor.

While the heater jacket is being held in its proper place in the vibratory carrier, the lower tapered seat for the jacket must be 75 elevated and the intermediate clamp on the carrier set to grip the jacket. Meantime the hook rod 101 is temporarily held in raised position.

A knurled knob or handle 105 on the 80 lower end of the hook rod 101 provides ready means by which the same may be raised.

The mechanism for temporarily holding the hook rod 101 in raised position 85 comprises a head 106 rigidly fastened in the guide pipe 102 and having a tapered opening for receiving a split friction cone 107. By means of a cap nut 108, the friction cone 107 is forced in the tapered opening of the 90 head 106 until the friction between the cone 107 and the hook rod 101 is sufficient to hold the rod in any raised position to which it may be adjusted. The cap nut 108 may then be locked to the head 106 as by a set 95 screw 108'.

After the heater jacket has been securely clamped in the vibratory carrier, the hook 100 rod 101 is clamped in raised position by the clamping screw 103, so as to avoid the possibility of the hook rod 101 falling due to the vibration of the machine while the carrier is being vibrated. Thus the resistor 8 is maintained under the proper tension to secure the desired results while the jacket is 105 being filled with insulation.

Belt shifter.

The belt shifter (see Figs. 8, 14, 15 and 16) is provided for shifting the belt 75 from 110 the pulley 71 fixed on the vibrator shaft 60 to the pulley 70 loose thereon and thus stop the operation of the filling unit when the heater jacket has been filled to the desired height with insulation.

This belt shifter comprises a lever 109 pivoted on a pin 109' secured to the frame cross rail 20 and having at its upper end a pair of fingers 110 for embracing the belt 75 to be shifted thereby, and a spring actuated 115 rod 111 connected thereto and normally held restrained by a solenoid 112.

The horizontally disposed actuating rod 111 connected to the lever 109 is slidably mounted in openings provided in projections 113 of a bracket 114 screwed or otherwise rigidly fastened to the frame cross rail 20.

A coil spring 115 encircling the rod 111 and interposed between a collar 116 fastened 125

thereto and the left frame projection 113 forces the rod to the right unless restrained.

Movement of the rod 111 is restrained by a latch 117 pivoted on the bracket 114 and 5 engaging a pin 118 secured to the collar 116.

The latch 117 is connected to the solenoid plunger 119 so that when the solenoid winding 120 is energized by the closure of the controller switch, as will more fully herein- 10 after appear, the raising of the plunger withdraws the latch 117 from the pin 118, thus allowing the spring 115 to move the rod 111 to the right until the collar 116 abuts the right bracket projection 113.

15 Movement of the rod in the other direction is limited by a collar 121 fastened thereon.

When the rod 111 is moved to right, the belt shifter shifts the driving belt from the fixed to the loose vibrator shaft pulley.

20 The solenoid 112 is mounted on a plate 122, of fibre or other insulating material, screwed or otherwise fastened to the frame cross rail 20.

The solenoid 112 is provided with two 25 terminals 123 and 124, to which the respective ends of the solenoid winding 120 are connected.

These terminals are in the form of contact rods extending through the insulating plate 122, enlarged openings in the frame cross rail 20 and a plate 125, of slate or other insulating material, rigidly fastened to the back of the frame cross rail 20. Each of 30 these contact terminal rods 123 and 124 is provided with appropriate nuts and washers by which electric conductors may be fastened thereto.

The electric conductor 126 leading to a 35 contact of the controller switch is connected to the rear end of the terminal rod 123, while the conductor 127 leading to one pole of a source of current supply is connected to the rear end of the terminal rod 124.

Similar terminal rods 128 and 129 extending 40 through the fibre insulating plate 122, enlarged openings in the frame cross rail 20, and the slate insulating base 125 are provided at their forward ends with respective contact blocks 130 and 131, and at 45 their rear ends with appropriate nuts and washers by which the electric conductors may be connected therewith.

The conductors 126 and 132 extend up 50 through a vertically disposed protective conduit to the controller, while the conductors 127 and 133 extend through a horizontally disposed conduit 127' to a source of current supply.

Each of the contact blocks 130 and 131 is 55 mounted upon the fibre insulating plate 122 and is rigidly fastened thereto by the respective connected conductor rods and positioning pins.

An electric conductor 132 leading to a 60 contact of the controller switch is connected

with the conductor rod 128, while an electric conductor 133 extending to the other pole of a source of current supply, is connected to the conductor rod 129.

Connection between the contact blocks 130 70 and 131 is effected by means of a contact spring 134 rigidly fastened to the upper end of a contact strip 135 carried by an insulating block 135' secured to the slidable rod collar 116.

Thus, when the latch 117 disengages the pin 118 upon the energization of the solenoid winding 120, the compression spring 115 moves the rod 111 to the right, shifting the belt from the fixed to the loose pulley 80 and moving the contact spring 134 away from and out of engagement with the contact blocks 130 and 131.

Therefore, when the belt is shifted the solenoid energizing circuit is opened between 85 the contact blocks.

In order that the belt may be readily shifted and the operating of the filling unit stopped in case of an emergency, the latch 117 is provided with a downwardly extending rod 136 having a knob 136' at the lower end thereof. Thus, by raising the rod, the latch is caused to disengage the pin 118 to allow the compression spring to operate the belt shifter.

Controller.

The controller (see Figs. 18 to 21) by which the energizing or operating circuit of the belt shifter solenoid is controlled comprises a switch having a movable contact 137 and a pair of adjustable stationary contacts 138.

The movable contact 137 is supported at the top of the tamper tube 7, and is insulated therefrom by an insulating bushing 139 and from the tension rod or wire 98 by a bushing 140.

The adjustable contacts 138 of the controller switch are secured to an insulating bushing 141 and are connected to respective contact rods 142 fastened to and insulated from an arm 143 so as to be movable therewith, as will more fully hereinafter appear.

An insulating guard 144 for the contacts 138 is fastened to the insulating bushing 141 so as to provide a casing for the contacts and insulate them from the metallic guide tube 82 and the extension 82' therefor.

The guide tube extension 82' allows the contact brush casing 146 to be raised when a long heater jacket is to be filled, so the movable controller contact 137 carried by the tamper 7 will not engage the stationary controller contacts 138 until the jacket is filled with insulation. The tips of screws 83^a mounted in the guide tube extension extend into longitudinal slots 83^b in the guide tube 82 so as to prevent any turning 138^a

movement of the guide tube extension 82' when the same moves up or down.

Spring contact brushes 145 mounted in an insulating casing 146 are positioned so as to engage the respective contact rods 142 connected with the switch contacts 138.

The insulating casing 146 is supported by the guide tube extension 82' and is fastened thereto at its upper end by means of set 10 screws 146' or other fastening means.

These contact brushes 145 are connected with terminals 147 and 147' also mounted in the insulating casing 146.

The electric conductor 126 connected with 15 one terminal of the solenoid winding 120 is connected to one of the controller terminals 147 by means of a binding screw or other fastening means. Likewise the electric conductor 132 connected to the solenoid contact block 130 is connected to the other controller terminal.

The electric conductors 126 and 132 extend through and are protected by a conduit 126' clamped to the bracket arms 25 and having an insulating bushing 132' in the upper end thereof.

The controller terminals 147 and 147' are mounted in pockets provided in the casing 146 and are protected by an insulating guard 30 148 through which the electric conductors 132 and 126 extend. The insulating casing 146 may also be provided with a cap or cover 149 of insulating material.

The solenoid operating circuit may be 35 traced from one pole of a source of current supply (not shown) over conductor 127, terminal 124, solenoid winding 120, terminal 123, conductor 126, terminal 147, brush 145, contact rod 142, controller contact 138, movable controller contact 137, contact rod 142, brush 145, terminal 147', conductor 132, terminal 128, contact block 130, contact spring 134, contact block 131, terminal 129, and conductor 133 to the other 45 pole of the source of current supply.

In order that the filling unit may be stopped automatically at the proper time when the heater jackets of different lengths are being filled, the controller switch contacts 50 138 are adjustably supported within the guide tube 82; and these contacts are so interlinked with the adjustable upper bracket 27 of the vibratory carrier that when this bracket is raised or lowered on 55 the carrier, the controller switch contacts 138 are raised or lowered the same distance.

For this purpose the upper arm of the adjustable bracket 27 is connected by means of a supporting rod 150 with the arm 143 which 60 supports the adjustable controller switch contacts 138. The contact supporting arm 143 is rigidly fastened to the upper end of the supporting rod 150 which extends through a guide tube 151 clamped in the 65 frame brackets 25. A bushing 151' at the

upper end of the guide tube 151 prevents any turning movement of the supporting rod 150 which for the major portion of its length is square or rectangular in cross-section.

In order that the vibrations of the carrier 3 transmitted to the controller switch contacts 138 may be reduced, a resilient connection between the carrier bracket 27 and the supporting rod 150 is provided. This resilient connection forms a cushioned seat for the supporting rod.

The cushioned seat provided for the rod 150 comprises a cylinder 152 provided with a piston 153 connected to the supporting rod 150 by means of a piston rod 154. The piston 153 is seated upon a compression spring 155 arranged within the cylinder 152 below the piston.

The cylinder 152 is rigidly fastened to an 85 extension of the upper arm of the carrier bracket 27 by means of a flanged internally threaded collar 156 bolted or otherwise fastened to the bracket extension. The cylinder 152 is provided with a head 157, the upper 90 end of which is closed by a cap 157' having a central opening therein for the piston rod 154.

To provide for relatively close adjustment of the switch contacts 138 the piston rod 154 95 and the supporting rod 150 are connected by means of a turnbuckle 158.

The turnbuckle 158 may be locked in adjusted position by nuts 158' at each end thereof so as to prevent change of position 100 thereof due to vibration of the vibratory carrier.

When the upper carrier bracket 27 is raised or lowered, the supporting rod 150 and the contact carrying arm 143 fastened thereto will move therewith so that the controller switch contacts 138 will move the same distance that the carrier bracket is moved.

Ordinarily when the carrier of the filling 110 unit is to be arranged for filling heater jackets of a particular length, the position of the lower carrier bracket 28 on the vibratory carrier is changed accordingly, so that the distance between the upper and lower brackets 115 is such that the heater jacket may be accommodated therebetween.

However, when placing a heater jacket in the vibratory carrier, further adjustment may be necessary in order that the heater jacket may be rigidly held at both its upper and lower ends. Therefore, if further adjustment is needed after the heater jacket is placed in the vibratory carrier, this adjustment is made by raising or lowering the upper carrier bracket 27.

While but one embodiment has been illustrated and described, it is obvious that the invention contained herein is susceptible of various other embodiments and adaptations,

The invention claimed is:

1. In a machine for filling the jacket of an electric heater with insulation and separating therefrom the heater resistor arranged therein, the combination of a vibratory carrier for the jacket, a container from which insulation is discharged into the jacket, a tamper periodically lifted and dropped to compress the insulation in the jacket, a friction shoe for engaging the tamper to hold the same in elevated position, and means for moving the shoe into and out of engagement with the tamper.
2. In a machine for filling the jacket of an electric heater with insulation and separating therefrom the heater resistor arranged therein, the combination of a vibratory carrier for the jacket, a container from which the insulation is discharged into the jacket, a tamper periodically lifted and dropped to compress the insulation in the jacket, clamping means for engaging the tamper to hold the same in elevated position, and an operative handle for the clamping means, said handle being weighted at one end so as to prevent operation of the clamping means while the carrier is being vibrated.
3. A machine for filling the jacket of an electric heater with insulation and separating therefrom the heater resistor arranged therein, having, in combination, a vibratory carrier for the jacket, a container for the insulation, a funnel positioned over the upper and open end of the jacket, a spout for the container through which insulation is discharged into the funnel, and a piston in the container for assisting in discharging insulation therefrom.
4. A machine for filling the jacket of an electric heater with insulation and separating therefrom the heater resistor arranged therein, having, in combination, a vibratory carrier for the jacket, a container for the insulation, means for guiding the insulation from the container into the jacket, and a piston in the container for assisting in the discharge of insulation therefrom.
5. A machine for filling the jacket of an electric heater with insulation and separating therefrom the resistor arranged therein, having, in combination, a vibratory carrier for the jacket, a container for the insulation, means for guiding the insulation from the container into the jacket, and means including a piston in the container and mechanism for vibrating the container to cause the insulation to be discharged from the container.
6. In a machine for filling the jacket of an electric heater with insulation and separating therefrom the heater resistor arranged therein, the combination of a carrier for the jacket, a rotary vibrator for rapidly vibrating the carrier, means for feeding the insulation into the jacket, a tamper for compress-

ing the insulation therein, and a tamper lifter geared to and driven by the vibrator shaft.

7. A machine for filling the jacket of an electric heater with insulation and separating therefrom the heater resistor arranged therein, having, in combination, a vibratory carrier for the jacket, a rotary vibrator therefor, a container from which insulation is discharged into the jacket, and means for stopping the vibration of the carrier when the jacket is filled with insulation comprising an electromagnet controlling the vibrator, a circuit closing switch for the electromagnet operating circuit controlled by the height of the insulation in the jacket, and means actuated by the electromagnet for opening the operating circuit thereof.

8. A machine for filling the jacket of an electric heater with insulation and separating therefrom the heater resistor arranged therein, having, in combination, a vibratory carrier for the jacket, a power driven vibrator therefor, a container from which insulation is discharged into the jacket, and means, for disconnecting power from the vibrator when the jacket is filled with insulation, comprising an electromagnet, a spring operated power disconnecting rod normally held against operation by the electromagnet, and a circuit closing switch for the electromagnet operating circuit controlled by the height of insulation in the jacket.

9. A machine for filling the jacket of an electric heater with insulation and separating therefrom the heater resistor arranged therein, having, in combination, a vibratory carrier for the jacket, a power driven vibrator therefor, a container from which insulation is discharged into the jacket, and means, for disconnecting power from the vibrator when the jacket is filled with insulation, comprising an electromagnet, a spring operated power disconnecting rod normally held against operation by the electromagnet, a circuit closer in the electromagnet operating circuit controlled by the height of insulation in the jacket, and means actuated by the electromagnet for opening the operating circuit thereof.

10. A machine for filling the jacket of an electric heater with insulation and separating therefrom the heater resistor arranged therein, having, in combination, a vibratory carrier for the jacket, a power driven vibrator therefor, a container from which insulation is discharged into the jacket, and means, for disconnecting power from the vibrator when the jacket is filled with insulation, comprising an electromagnet, a spring operated power disconnecting rod normally held against operation by the electromagnet, a circuit closing switch for the electromagnet operating circuit controlled by

- the height of insulation in the jacket, and a pair of stationary contacts in the operating circuit normally bridged by a contact arm carried by the power disconnecting rod.
- 5 11. A machine for filling the jacket of an electric heater with insulation and separating therefrom the heater resistor arranged therein, having, in combination, a container arranged to discharge insulation therefrom
- 10 into the jacket, a tamper for compressing the insulation in the jacket, power driven mechanism for vibrating the container and for periodically raising the tamper and allowing the same to drop, an electromagnet, a spring operated rod, for disconnecting power from the mechanism, normally held against operation by the electromagnet, and a circuit closing switch for the operating circuit of the electromagnet adapted to be
- 15 closed when insulation in the jacket reaches a predetermined height.
12. In a machine for filling the jacket of an electric heater with insulation and separating therefrom the heater resistor arranged therein, the combination of a vibratory carrier having upper and lower brackets in which the jacket may be seated, one bracket being adjustable so that jackets of different lengths may be accommodated, a power
- 20 driven vibrator for the carrier, means for introducing insulation into the jacket, an electromagnet for disconnecting power from the vibrator, a circuit closing switch, for the operating circuit of the electromagnet, having
- 25 a relatively stationary contact supported by the adjustable carrier bracket and a movable contact adapted to be moved toward the relatively stationary contact as the jacket fills with insulation, and means for absorbing the
- 30 vibration of the carrier so as to reduce the movement of the relatively stationary contact.
13. In a machine for filling the jacket of an electric heater with insulation and separating therefrom the heater resistor arranged therein, the combination of a vibratory carrier having upper and lower brackets in which the jacket may be seated, one bracket being adjustable so that jackets of
- 35 different lengths may be accommodated, a power driven vibrator for the carrier, means for introducing insulation into the jacket, an electromagnet for disconnecting power from the vibrator, a circuit closing switch, for the operating circuit of the electromagnet, having relatively movable and stationary contacts, a vertically disposed rod having an arm from which the stationary contact is suspended, a vibration absorbing dash pot carried by the adjustable carrier bracket and having a piston connected to the vertically disposed rod, and means for moving the movable contact into engagement with the stationary contact when the jacket is
- 40 filled to a predetermined height.
14. A machine for filling the jacket of an electric heater with insulation and thus separating therefrom the heater resistor arranged therein, having, in combination, a vibratory carrier for the jacket, a container for the insulation, means for discharging insulation from the container into the jacket, and means for keeping the resistor under tension as the insulation is being introduced into the jacket, said tensioning means comprising an adjustable vertically extending rod having an arm at its upper end and a wire or cable fastened at its upper end to the arm, and a hook at its lower end for engaging the resistor. 70
15. A machine for filling the jacket of an electric heater with insulation and thus separating therefrom the heater resistor arranged therein, having, in combination, a vibratory carrier for the jacket, a container for the insulation, means for discharging insulation from the container into the jacket, and means for keeping the resistor under tension as the insulation is being introduced into the jacket, said tensioning means comprising an adjustable vertically extending rod having an arm at its upper end and a wire or cable fastened at its upper end to the arm, and a hook at its lower end for engaging the resistor. 75
16. A machine for filling the jacket of an electric heater with insulation and separating therefrom the heater resistor arranged therein, having, in combination, a vibratory carrier provided with upper and lower brackets between which the jacket may be seated and adjustable thereon so as to accommodate jackets of different lengths, a container supported by the upper bracket and arranged to discharge insulation therefrom into the jacket, power driven mechanism for vibrating the carrier, and means, for disconnecting power from the vibrating mechanism when the jacket is filled to a predetermined height, comprising a power disconnecting electromagnet, a circuit closing switch for the electromagnet operating circuit, a pair of relatively stationary contacts for the switch supported by and adjustable with the upper carrier bracket, a bridging contact for the switch adapted to be moved into engagement with the stationary contacts when the jacket is filled to a predetermined height, and a pair of contact shoes connected to the electromagnet operating circuit and engaging the respective stationary switch contacts. 90
17. In a machine for filling the jacket of an electric heater with insulation and separating therefrom the heater resistor arranged therein, the combination of a vibratory carrier provided with upper and lower brackets between which the jacket may be
- 95
- 100
- 105
- 110
- 115
- 120
- 125
- 130

seated and adjustable thereon so as to accommodate jackets of different lengths, a container supported by the upper carrier bracket and arranged to discharge insulation therefrom into the jacket, a tamper for compressing the insulation in the jacket, a guide tube for the tamper extending above the vibratory carrier, power driven mechanism for vibrating the carrier and for periodically lifting and allowing the tamper to drop, an electromagnet controlling the disconnection of power from the mechanism, a circuit closing switch, for the electromagnet operating circuit, having a pair of relatively stationary contact rods supported by and adjustable with the upper carrier bracket, a cooperating bridging contact carried by the tamper, a pair of contact shoes connected to the operating circuit and engaging the respective rods, and an adjustable extension for the upper end of the guide tube supporting the contact shoes.

18. In a machine for filling the jacket of an electric heater with insulation and thus separating therefrom the heater resistor arranged therein, the combination of a vibratory carrier for the jacket, a container from which insulation is discharged into the jacket, a tamper periodically lifted and dropped to compress the insulation in the jacket, a clamping screw having a soft metal tip for engaging the tamper to hold the same in lifted position, and an operating handle for the clamping screw, the handle being weighted at one end so as to prevent operation of the clamping screw due to vibration of the carrier.

19. In a machine for filling the jacket of an electric heater with insulation and thus separating therefrom the heater resistor arranged therein, the combination of a vibratory carrier for the jacket, a container from which insulation is discharged into the jacket, a tamper periodically lifted and dropped to compress the insulation in the jacket, a clamping screw for engaging the tamper to hold the same in lifted position, and an operating handle for the clamping screw, the handle being weighted at one end so as to prevent operation of the clamping screw due to vibration of the carrier.

20. A machine for filling the jacket of an electric heater with insulation and thus separating therefrom the heater resistor arranged therein, having, in combination, a vibratory carrier for the jacket, a container for the insulation, a funnel positioned over the upper and open end of the jacket, a spout for the container through which insulation is discharged into the funnel, and an indicator controlled by the height of insulation in the container and indicating the quantity of insulation therein.

21. A machine for filling the jacket of an electric heater with insulation and thus sep-

arating therefrom the heater resistor arranged therein, having, in combination, a vibratory carrier for the jacket, a container for the insulation, a funnel positioned over the upper and open end of the jacket, a spout for the container through which insulation is discharged into the funnel, a piston in the container for assisting in discharging insulation therefrom, and a piston rod extending through the upper end of the container and indicating the quantity of insulation therein.

22. A machine for filling the jacket of an electric heater with insulation and thus separating therefrom the heater resistor arranged therein, having, in combination, a vibratory carrier for the jacket, a container for the insulation mounted on the carrier, a funnel positioned over the upper and open end of the jacket, a spout for the container through which insulation is discharged into the funnel, a piston in the container for assisting in discharging the insulation therefrom, a piston rod extending through the upper end of the container and indicating the quantity of insulation therein, and a valve in the spout for regulating the flow of insulation therethrough.

23. A machine for filling the jacket of an electric heater with insulation thus separating therefrom the heater resistor arranged therein comprising a vibratory carrier, upper and lower brackets mounted thereon between which the jacket may be positioned, a seat formed of yielding material on the lower bracket for receiving the lower end of the jacket, a funnel on the upper bracket beneath the lower end of which the upper and open end of the jacket may be positioned, and a container for insulation mounted on the upper bracket and provided with a spout through which insulation is discharged into the funnel.

24. A machine for filling the jacket of an electric heater with insulation thus separating therefrom the heater resistor arranged therein comprising a vibratory carrier, upper and lower brackets mounted thereon between which the jacket may be positioned, a seat formed of yielding material on the lower bracket for receiving the lower end of the jacket, a funnel on the upper bracket beneath the lower end of which the upper and open end of the jacket may be positioned, a container for insulation mounted on the upper bracket and provided with a spout through which insulation is discharged into the funnel, and a clamp on the carrier arranged to grip the jacket intermediate the ends thereof.

25. A machine for filling the jacket of an electric heater with insulation thus separating therefrom the heater resistor arranged therein comprising a vibratory carrier, upper and lower brackets mounted thereon between which the jacket may be positioned,

- a seat formed of yielding material on the lower bracket for receiving the lower end of the jacket, a funnel on the upper bracket beneath the lower end of which the upper 5 and open end of the jacket may be positioned, a container for insulation mounted on the upper bracket and provided with a spout through which insulation is discharged into the funnel, and a regulating 10 valve for the spout.
26. In a machine for filling the jacket of an electric heater with insulation and separating therefrom the heater resistor arranged therein, the combination with a vi- bratory carrier for the jacket, of a container 15 from which insulation is discharged into the jacket, a tamper to be intermittently lifted and dropped to compress the insulation in the jacket, a plurality of spring supported friction shoes for engaging and lifting the tamper, and means for moving said shoes 20 into and out of engagement with the tamper.
- In witness whereof we have hereunto subscribed our names.

EDWIN N. LIGHTFOOT.
